UNITED STATES PATENT OFFICE.

JOHN R. GRIFFITH AND LESLIE G. COSPER, OF INDEPENDENCE, KANSAS.

WELL-DRILLING MACHINE.

SPECIFICATION forming part of Letters Patent No. 787,842, dated April 18, 1905.

Application filed July 5, 1904. Serial No. 215,324.

To all whom it may concern:

Be it known that we, JOHN R. GRIFFITH and LESLIE G. COSPER, citizens of the United States, residing at Independence, in the county of Montgomery and State of Kansas, have invented a new and useful Well-Drilling Machine, of which the following is a specification.

This invention relates to well-drilling machines; and it has for its object to provide for the construction and operation of a machine of this class in a simple, feasible, durable, and inexpensive manner.

The invention especially relates to the mounting of the bull-wheel shaft upon the main shaft of the machine, the said bull-wheel shaft being tubular and capable of being coupled to or disconnected from the main shaft, as may be required.

Another object of the invention is to provide an improved spudding or jogging mechanism which may be used interchangeably with the walking-beam when desired.

Further objects of the invention will readily appear as the nature of the same is better understood.

With these and other ends in view the invention consists in the improved construction and novel arrangement and combination of parts, which will be hereinafter fully described, and particularly pointed out in the claim.

In the accompanying drawings has been illustrated a simple and preferred form of embodiment of the invention, it being understood, however, that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a top plan view of a machine constructed in accordance with the principles of the invention, the walking-beam having been removed and the samson-post having been broken away for the purpose of exposing the subjacent construction. Fig. 2 is a side elevation showing what may

be designated the "front" side of the machine. Fig. 3 is a side elevation showing the rear side.

Corresponding parts in the several figures are indicated by similar characters of reference.

The frame F of the machine is preferably supported upon front wheels 11 and hind wheels 22 for convenience in transportation, the axle of the front and rear trucks being provided with bolsters 3 for the purpose of supporting the frame in a level position. The frame is composed of front and rear side pieces 5 and 6, end pieces 7 and 8, and intermediate cross-bars 9, of which latter any desired number may be used. At the rear end of the frame is constructed a tool-box, and braces 11 extend obliquely from the front and rear axles to the body of the frame, which is thereby trussed and reinforced.

The members 5 6 of the frame are provided with berrings for the main shaft 12, having at its front end the main crank 13 and at its rear end the band-wheel 14, which receives motion in the usual manner by means of a belt or band from the source of power. (Not shown.) The crank 13 and the band-wheel 14 are both securely mounted upon the main shaft by means of keys 15, and both of said members are located adjacent to the outer sides of the frame-beams 5 and 6.

The main shaft carries between the side members 5 and 6 a tubular shaft 16, carrying the bull-wheel 17 and a bull-wheel flange 18, which combine with the shaft 16 to form a reel upon which the drilling-rope 19 is wound and to which said rope is in the usual manner attached.

The end of the tubular bull-wheel shaft 16 which projects beyond the bull-wheel is provided with notches 20, adapted to engage lugs 21, formed upon a collar 22, which is mounted slidably upon the main shaft, feathers 23 being employed to cause the collar 22 to rotate with said main shaft. The collar 22 cooperates with the notched end of the bull-wheel shaft to constitute a clutch whereby the bull-wheel shaft, with its attachments, may be locked upon or disconnected from the main shaft 12, as may be desired. The collar 22

- has an annular groove 24, engaged by a ring or sleeve 25, having diametrically opposite pins whereby it engages the bifurcated and slotted end of a lever 29, which is fulcrumed 5 upon one of the cross-braces 9 of the frame and which extends to a point at which it may be conveniently manipulated by the operator, who may thus connect the bull-wheel shaft with or disconnect it from the main shaft 12.
- 10 30 designates the sand-reel, which is mounted upon a shaft 31, one end of which is journaled loosely in a boxing 32 and the opposite end of which is eccentrically journaled in a circular boxing 33, capable of rotating within 15 a housing 34 upon the frame-beam 6. The shaft 31 is provided with collars 35 to provide against displacement longitudinally of its axis of said shaft. The rotary boxing 33 has an arm 33^a, which is connected by a reach or connecting-rod 36 with a crank 37 upon a shaft 38, which is journaled upon the frame member 6 in a convenient position to the operator. The crank-shaft 38 has a lever 39, constituting a handle by means of which it may be conveniently operated.
- 10 30 The end of the sand-reel shaft 31 which projects beyond the rotary boxing or bearing 33 carries a friction-wheel 40, which by manipulating the handle 39 of the crank-shaft 38 may be thrown into engagement with the periphery of the band-wheel 14, thereby causing the sand-reel shaft to be rapidly rotated. Secured to the frame adjacent to the side of the frame-wheel 40 opposite to the band-wheel 14 is a brake-block 41, with which by a reverse movement of the handle 39 the friction-wheel 40 may be thrown into contact for the purpose of checking the rotation of the band-wheel when it shall be deemed necessary 35 40 to do so during the descent of the sand-pump.
- 42 is a sand-line which is carried over suitable guiding means (not shown) to its point of connection with the sand-pump.
- 43 is a rock-shaft which is mounted in suitable bearings upon the frame-beams 5 and 6 and which is provided at its forward end adjacent to the outer side of the frame-beam 5 with a crank 44. The shaft 43 also carries at an intermediate point between the frame-beams 5 and 6 a crank 45, having a wrist-pin 46, upon which is journaled a grooved pulley 47, adapted to engage the drill-rope 19. The crank 44 of the shaft 43 has a wrist-pin 48, which is capable of being connected with a wrist-pin 49 upon the main crank 13 by means of a pitman 50. The main crank 13 being somewhat shorter than the crank 44, the latter will when connected up with the crank 13 by means of the pitman 50 receive a rocking or oscillatory motion, causing a similar movement to be imparted to the crank 45, carrying the jogging-wheel or spudding-wheel 47, which is effective in imparting a jogging motion to

the drill-rope, which is guided in the usual manner over a pulley at the upper end of the mast or derrick, the lower extremity of which has been indicated at 51. The samson-post 52, which is supported upon the main frame, carries the walking-beam 53. The walking-beam may be connected with the crank 13 by means of a pitman 54, having a stirrup 55 engaging a transversely-grooved plate 56 upon the upper side of the walking-beam, said plate combining with a superimposed transversely-grooved plate 57 to form a bearing for the cross-bar 58 of the stirrup, connecting-bolts 59 being provided, whereby the bearing may be adjusted.

To a suitable point of attachment, such as one of the cross-braces 9, adjacent to the bull-wheel 17, is secured one end of a brake-strap 60, which passes around the bull-wheel and has its free end connected with a crank 61 upon the shaft 62, which is journaled upon the cross-brace 9. The crank-shaft 62 has an arm or lever 63, which is connected by a reach or connecting-rod 64 with a crank 65 upon a shaft 66, suitably journaled in the vicinity of the clutch-operating lever 29 and the operating-lever 39, by means of which the friction-wheel 40 is actuated. The crank-shaft 66 has a lever or handle 67, by means of which it may be actuated to tighten the brake-strap upon the bull-wheel, thereby to check the rotation of the latter.

The operation and advantages of this invention will readily appear from the foregoing description, taken in connection with the drawings hereto annexed. It will be observed that in this machine transmission of power through the medium of gear-wheels, chains and sprockets, and the like is entirely avoided, thereby largely avoiding unnecessary rattling and straining of the parts of the machine, as well as the inordinate noise usually caused by drilling machinery. The general construction, it will be seen, is extremely simple and a comparatively small number of parts is employed in the construction of the device. The main shaft, upon which the band-wheel is mounted, directly operates not only the walking-beam, or when desired the spudding and jogging mechanism, but also the bull-shaft, which is tubular in shape, as shown, and is mounted directly upon the main shaft and capable of connection with or disconnection therefrom, as may be desired. When it shall be desired to drive the main shaft and its connections independently of the bull-shaft, the bull-wheel may be locked against rotation by the brake means provided for the purpose. Said brake means, however, are capable of being readily controlled, so that the drill-rope when desired may be paid out from the bull-shaft during the operation of the main shaft.

Other advantages of the device will readily suggest themselves to those skilled in the art to which the invention appertains.

Having thus described the invention, what is claimed is—

In a well-drilling machine, a frame having side members, a driven main shaft, a tubular bull-shaft mounted upon said main shaft, means for connecting said bull-shaft operatively with, and disconnecting it from the main shaft, a crank at the end of the latter, a rock-shaft journaled upon the frame and having a crank at its outer end, a pitman con-

necting said crank with the crank upon the main shaft, a crank upon the rock-shaft intermediate of the side members of the frame, and a drill-rope-engaging pulley supported by said crank. 15

In testimony that we claim the foregoing as our own we have hereto affixed our signatures 20 in the presence of two witnesses.

JOHN R. GRIFFITH.
